UNITED STATES PATENT OFFICE.

HENRY F. LIPPITT, OF PROVIDENCE, RHODE ISLAND, ASSIGNOR TO THE COP DYEING COMPANY, OF SAME PLACE.

HOLLOW PERFORATED TUBE FOR DYEING.

SPECIFICATION forming part of Letters Patent No. 394,778, dated December 18, 1888.

Application filed August 30, 1888. Serial No. 284,154. (No model.)

To all whom it may concern:

Be it known that I, HENRY F. LIPPITT, a citizen of the United States, residing at Providence, in the State of Rhode Island, have invented certain new and useful Improvements in Hollow Perforated Tubes for Dyeing, Bleaching, or otherwise Treating Yarns in Cops, of which the following is a specification.

This invention relates to, and is applicable to in connection with, certain improvements in the art of dyeing, bleaching, or otherwise treating cotton and other yarns in the form of cops, by either sucking or forcing liquid dyes, or other liquids used in dyeing, bleaching or otherwise treating the cops, through the cops when mounted upon hollow perforated tubes, skewers, or injection spindles, which extend respectively through the cops and render every portion of each cop subject to the action of the said liquids,—the said improvements having been invented by August Graemiger and constituting the subject matter of United States Letters Patent No. 368,715, granted August 23d, 1887, to the Crompton Company assignee of said Graemiger.

In the aforesaid practice of dyeing yarns in cops upon hollow perforated injection tubes, it is obvious that the tube, notwithstanding the fact that it is perforated, must be so formed as to its perforations that the cop can be easily applied and removed without damage to such of its threads as form the walls of its core or axial aperture and therefore come into immediate contact with the surfaces of the tube. This is the more a necessity because the cop, after the shrinkage incident to the operation of injection, clings so tightly to the tube as to be with difficulty manually removed, and because the integrity of the internal cop threads must be perfectly maintained. With these conditions in view, hollow tubes, adapted to be introduced within the hollow core of a cop to be bleached or otherwise treated, have been provided with a series of elongated and, in fact, double-pointed perforations or openings, which by reason of their form have permitted of the application and removal of the cop without injury to its internal threads. Notwithstanding the fact, however, that injection tubes of the foregoing character possess, in the matter of the application and re-

moval of the cop, many advantages over tubes having perforations of other forms more likely to cut the internal threads of the hollow axis of the cop,—it has yet been found in practice that the cop in its shrinkage clings so tightly to said tube as to render difficult and sometimes imperfect the operation or act of injection through the thickest portion of said cop, or that portion which, as cops are commonly made, is just above the upper termination of the cop tube.

It is the object of my invention to so construct an injection tube or spindle that a cop cannot only be readily applied to and removed from it, but also be readily injected or saturated with the dye stuff throughout the substance of its region of greatest diameter, and these objects I accomplish by drawing in, narrowing, double-tapering, or contracting, that portion of the tube itself which, when the cop has been applied, comes opposite to the thickest portion of said cop, so as to render said tube at said portion of less diameter than it would otherwise be were its taper or cylindric contour continued uniform throughout its length.

In the accompanying drawings, Figure 1 is a central, vertical, sectional, elevation through a hollow perforated injection tube embodying my invention, and equipped with a cop to be injected upon it. Fig. 2 is a side elevation of the tube of Fig. 1. Figs. 3, 4, and 5, are magnified, fragmentary, central, vertical, sectional, elevations, through sections of a tube susceptible of embodying my invention and illustrative of forms of perforations or openings which are the equivalents of the lenticular openings shown in the tubes of Figs. 1 and 2. Fig. 6 is a similar view illustrative of such an opening as I prefer to employ.

Similar letters of reference indicate corresponding parts.

The injection tube A is formed of any material, preferably metal, capable of withstanding the chemical action of liquid dyes and other liquids, and the temperatures employed in the operation of dyeing, bleaching, drying, or otherwise treating the cops. The tube is closed at its upper extremity but otherwise is hollow throughout.

a designates the perforations through the

wall of the tube, which, as stated, are preferably of forms resorted to by Graemiger. These perforations it is to be understood are no part of this invention.

a^x is the usual annular gage flange common in these tubes, which is preferably stamped out as a flat ring, slid upon the tube, and secured by solder. This flange is a device of convenience serving to gage the position of the cop upon the tube and to protect against unraveling or breaking down the lowermost or bottom threads of the cop, which is pressed very firmly against said flange.

B, Fig. 1, represents a cop in place upon the tube, and b a cop tube of any character, but preferably of knitted, woven or braided textile material stiffened with size.

Heretofore all injection tubes of the practical employment of which I have knowledge, have been formed with a regular and, usually, a very gradual or slight taper, uniform, however, throughout the length of the tube, which, geometrically considered, has, therefore, been a slightly conical body. In my invention I depart from this regular form, by narrowing or contracting that portion of the tube which in Fig. 2 is indicated as being included between the horizontal dotted lines xx and yy , the contracted portion being externally scooped out, so to speak, or, more strictly speaking, the tube being drawn in from two directions toward a central region to which the arrow z in Fig. 2 is shown as pointing, so as to be as to its bore strictured, and as to its exterior pinched in or narrowed. This construction results in the provision or existence, when the cop is applied, of an annular interspace between the axial aperture of the cop and the walls of the injection tube in the region of its contraction, such interspace being indicated in Fig. 1 by the solid black inking to which the arrows w point.

It will now be apparent that, in the operation of injection with a spindle embodying my improvements, the injecting liquid is afforded the freest opportunity for access to the walls of the axial aperture of the cop in the region of its greatest diameter or thickness, which is, of course, that region to which it is most desirable and at the same time most difficult for the liquid to have access to, as it is, of course, understood that thorough injection is easier as to the thinner portions of the cop than as to the thicker.

Figs. 1 and 2 of the drawings are as to the 55 features in which my invention resides slightly exaggerated for the purposes of clearer illustration, and in practice the walls of the cop close in about the contracted portion of the tube to an extent, perhaps, greater 60 than that illustrated, but yet not to an extent sufficient to prevent the thorough access of the liquid to the inner walls of the bore of the cop, as already explained.

I do not, of course, limit myself as to the 65 extent of the drawing-in, narrowing, or contraction of the tube diametrically considered, nor yet as to the longitudinal extent to which said contraction is carried, as these proportions fall within the province of the 70 contructer; the contraction, however, is necessarily intermediate of the length of the tube between its gage flange and its upper or outer end, and beyond each vanishing circumference of the contraction the tube extends a 75 predetermined distance of its full diameter or diameters, whether said tube be tapering, as is preferable, or cylindric as is possible.

It is of course to be understood that the contraction referred to is not necessarily an equal 80 contraction or a contraction from both ends of the spindle, and that the tube may be merely contracted from its base or larger end, so that, instead of being formed with a regular taper from base to apex, it is, about an 85 inch from the gage flange abruptly contracted to its smallest diameter, and thence proceeds to its apex with its regular taper.

Having thus described my invention, I 90 claim:—

As an article of manufacture, a hollow perforated tube, adapted to be introduced within the hollow bore of a cop to be dyed, bleached, or otherwise treated, which, intermediately of its length, is both diametrically and longitudinaly to a predetermined extent drawn in or contracted in diameter, substantially as and for the purposes specified.

In testimony that I claim the foregoing as my invention I have hereunto signed my 100 name this 25th day of August, A. D. 1888.

HENRY F. LIPPITT.

In presence of—

WILLIAM A. TUCKER,
HOLDEN BORDEN-BOWEN.
